CLAIM

The ornamental design for a stamper with cap, as shown and described.

DESCRIPTION

FIG. 1 is a top perspective view of a stamper with cap embodied in accordance with my design, with cap removed from a stamping surface of the stamper;

FIG. 2 is a bottom perspective view of the stamper;

FIG. 3 is a front view of the stamper with the cap;

FIG. 4 is a top plan view of the stamper with the cap;

FIG. 5 is a rear view of the stamper with the cap;

FIG. 6 is a bottom plan view of the stamper with the cap;

FIG. 7 is a right side view of the stamper with the cap;

FIG. 8 is a sectional view of the stamper taken along line 8—8 of FIG. 3;

FIG. 9 is a bottom plan view of the stamper without the cap; and,

FIG. 10 is a top plan view of the cap.
